UNITED STATES PATENT OFFICE.

ALBERT M. WOLTZ, OF BALTIMORE, MARYLAND, ASSIGNOR, BY MESNE ASSIGNMENTS,
TO LEON W. HIMMEL, ISADOR HIMMEL, AND JEANNETTE HIMMEL, COPARTNERS,
TRADING AS M. L. HIMMEL & SON, OF BALTIMORE, MARYLAND.

DUST-EXCLUDING DEVICE FOR SHELVING.

Application filed December 11, 1918. Serial No. 266,240.

To all whom it may concern:

Be it known that I, ALBERT M. WOLTZ, a citizen of the United States, residing at Baltimore, in the county of Baltimore City and 5 State of Maryland, have invented a new and useful Dust-Excluding Device for Shelving, of which the following is a specification.

This invention is a device for protecting the contents of store shelving and the like.

10 In that class of stores which carry stocks of piece goods, the problem of protecting the merchandise from dust is a serious one. Owing to the fact that it is necessary to frequently handle large bolts of cloth, the common practice is to store the bolts in open shelving, thereby exposing delicate fabrics to contamination by dust and other impurities, and in many instances where the shelves are close to the floor, there is risk of 15 spoiling expensive merchandise by carelessness of cleaners in splashing water while scrubbing the contiguous portions of the floor. In many stores it is customary to drape dust-protecting curtains in front of 20 the shelving at the close of business hours, but this method is merely a make-shift because the curtains do not fit closely to the shelving and they are not waterproof.

One of the objects of the invention is to 25 provide simple means whereby a dustproof and waterproof curtain may be employed to protect the goods on store shelving. A further object is to provide means whereby the curtain may be held close to the front of 30 the shelving when extended, and conveniently stored out of the way when not in use.

The invention will be hereinafter fully set forth and particularly pointed out in the 35 claims.

In the accompanying drawing:—

Figure 1 is a vertical sectional view illustrating store shelving with the invention applied thereto. Figure 2 is a horizontal sectional view. Figures 3 and 4 are detail views of the device for retaining the curtain in extended position.

Referring to the drawing, 10, 10, designate the end walls of stacks of shelves, the end 40 walls of each stack having means, such as cleats 11, for supporting shelves 12. Each stack of shelves is supported upon a base 13, provided with a chamber 14, having a removable cover 15, said cover being held in

position in suitable manner, such as by 55 screws 16. The stacks may be constructed on the unit system or as a single unit, according to preference, and the end walls of adjacent stacks are separated by spaces 17, said spaces being covered at the front of the 60 shelving by pilasters 18, or other suitable ornamental members.

Secured to the inner faces of the end walls 10, by suitable means such as screws 19, contiguous to the front edges thereof, are upright guide strips 20, provided with longitudinal guide channels 22.

Rotatably mounted in the chamber 14, is a roller 23, controlled by a spring (not shown) in a manner similar to the well-known curtain shade roller, and secured to said roller 23 at one end, is a curtain 24 of any preferred waterproof and dustproof material. The said end of the curtain is so attached to the roller that the action of the 70 spring will tend to wind the curtain upon the roller, the outer end of the curtain being attached in suitable manner to a lifting block 25. As shown, the end of the curtain is extended into an angular recess in the 75 block 25 and clamped in place by means of a cleat 26, secured in position by screws 27. The lifting block 25 is provided with guide flanges 28 extending into the channels 22, and the curtain is of sufficient width to permit its edges to also extend into said channels. It will be observed from the drawing 80 that when the curtain is wrapped around the roller 23, the block 25 is in its lowermost position with its upper edge approximately 85 flush with the top surface of the cover 15, the block extending downwardly over the front of the chamber 14. The downward movement of the block is limited in any desired manner, and upward movement of said 90 block is limited by the top of the case.

Attached to the top of each stack of shelving, is a plate 29 provided with a depending headed stud 30. The upper end of the lifting block is cut away to provide a recess 31, 100 which is covered by an angle plate 32, both members of which are slotted, as indicated at 33. The lifting block is also provided with a handle 34. A guide 35 for the curtain is also provided.

In operation, the roller 23 with the curtain 24 normally wrapped thereabout, is located within the chamber 14, the cover 15

being removable to permit of the installation of the roller through the top of the chamber, and also to permit ready access for purpose of repair and examination.

5 When it is desired to extend the curtain, the operator grasps the handle 34 and raises the block 25 to the top of the stack, and causes the stud 30 to enter the recess 31 through the slot 33 in the horizontal member of the angle plate 32, the upward movement of the block causing the curtain to unroll and extend over the front of the stack. A slight forward movement of the block 25 will then cause the head of the 10 stud to project through the slot 33 in the vertical member of the angle plate 32, the engagement thus effected serving to prevent separation of the block 25 and the stud 30, whereby the curtain is maintained 15 in extended relation in opposition to the tension of the spring roller 23. In this manner a dustproof and waterproof closure for the open shelving is provided, not only because the curtain extends over the front 20 of the shelving, but also because the edges of the curtain extend into the channels 22. When it is desired to expose the shelving, the block 25 is disengaged from the stud 30 by a rearward movement of the block, thereby 25 freeing the upper end of the curtain, whereupon the spring roller 23 will wind the curtain upon it, so that the latter will 30 be stored within the chamber 14.

From the foregoing it will be readily 35 understood that a simple and inexpensive dust and waterproof protection is obtained. It is also obvious that by constructing the curtain of fire-resisting material, such as asbestos, the additional advantage of fire 40 protection is obtained.

Having thus explained the nature of the invention and described an operative manner of constructing and using the same, although without attempting to set forth all 45 of the forms in which it may be made, or all of the forms of its use, what is claimed is:—

1. In a dust excluding structure for store furniture the combination of shelving consisting of a display portion and a supporting base, said base having an opening in

the front portion thereof, a spring actuated roller mounted within the normally useless space enclosed by said base, a dust excluding curtain connected at one end to said roller and extended through said opening, a lifting block secured to the other end of the curtain and closing said opening when the curtain is in rolled condition, means carried by the display portion for guiding said lifting block, and means at the top of the display portion for engaging said lifting block to hold the curtain extended over said display portion.

2. In a dust excluding structure for store furniture the combination of shelving consisting of a display portion and a supporting base, said base having an opening in the front portion thereof, the end walls of said display portion having guide channels, a spring actuated roller mounted within the 65 normally useless space enclosed by said base, a dust excluding curtain connected at one end to said roller, a lifting block engaging the other end of said curtain and shaped to close said opening when the curtain is in rolled condition, the ends of said lifting block engaging said guide channels, and means at the top of the display portion for 70 engaging the lifting block to hold the curtain extended over said display portion.

3. In a dust excluding structure for store furniture the combination of shelving comprising a display portion and a supporting base, said base providing a normally closed chamber, a removable cover for said chamber, a spring actuated roller mounted within said chamber, a dust excluding curtain connected at one end of said roller, said chamber having an opening between the forward end of said cover and the front portion of the base, a lifting block guided by the end walls of the display portion and positioned to close said opening when the curtain is in rolled condition, and means at the top of the display portion for engaging said lifting block to hold the curtain extended over said display portion.

In testimony whereof I have hereunto set my hand.

ALBERT M. WOLTZ.
